[57] CLAIM

The ornamental design for an auxiliary equipment console for data processing console grouping, as shown and described.

DESCRIPTION

FIG. 1 is a top, front, right side perspective view of an auxiliary equipment console for data processing console grouping showing our new design;

FIG. 2 is a top plan view thereof;

FIG. 3 is a front elevational view thereof;

FIG. 4 is a right side elevational view thereof, the left side being a mirror image;

FIG. 5 is a rear elevational view thereof;

FIG. 6 is a bottom plan view thereof.

The left and right side view of the FIG. 1 device are substantially identical.

FIG. 1

FIG. 2

FIG. 3

FIG. 4

FIG. 5

FIG. 6
